(57) **CLAIM**

The ornamental design for a body sculpting garment as shown and described.

DESCRIPTION

FIG. 1 is a front view of a body sculpting garment according to a first embodiment of the design;

FIG. 2 is a rear view thereof;

FIG. 3 is a right side view thereof;

FIG. 4 is a left side view thereof;

FIG. 5 is a front view of a body sculpting garment according to a second embodiment of the design;

FIG. 6 is a rear view thereof;

FIG. 7 is a right side view thereof;

FIG. 8 is a front view of a body sculpting garment according to a third embodiment of the design;

FIG. 9 is a rear view thereof; and,

FIG. 10 is a right side view thereof.

The broken lines illustrating a model are for environmental purposes only and form no part of the claimed design. The stippling in FIGS. 1-4 show shading that defines the contours of the design and does not reflect a particular surface ornamentation or material. The dashed broken lines along the surfaces of the garment in FIGS. 1-4 and 8-10 depict stitching that forms no part of the claimed design.
